CLAIM

The ornamental design for an inertial barrier container, as shown and described.

DESCRIPTION

FIG. 1 is a perspective view of an inertial barrier container showing our new design;

FIG. 2 is a front side elevation view thereof, the back side being a mirror image;

FIG. 3 is a right side elevation view thereof, the left side being a mirror image;

FIG. 4 is a top plan view thereof; and,

FIG. 5 is a bottom plan view thereof.
